Primary Examiner — Jennifer L Watkins*Assistant Examiner* — Samantha Lynne Brodowski(74) Attorney, Agent, or Firm — Kristin D. Wheeler(57) CLAIM

The ornamental design for a golf bag, as shown and described.

DESCRIPTION

The SOLE FIGURE is a side elevational view of a portion of a golf bag including the hip pad showing our new design. The evenly dashed broken lines depict portions of the golf bag and form no part of the claim. The dash-dot-dash broken line depicts the cut line of the section view and forms no part of the claim.

1 Claim, 1 Drawing Sheet(56)
